James C. Sproll, ATTORNEY

UNITED STATES PATENT OFFICE.

JESSE F. DRAPER, OF SEATTLE, WASHINGTON.

BUTT HOOK.

Application filed April 26, 1926. Serial No. 104,597.

This invention relates to butt hooks of the type especially designed for attachment to the hauling lines of logging apparatus for service in connection with the choker cables 5 of such apparatus, and aims primarily to provide a butt hook wherewith the ferruled terminal of a choker cable may be rapidly and readily coupled thereto and similarly uncoupled therefrom, and which embodies 10 means whereby uncoupling or unhooking of the ferruled terminal from the butt hook during hauling in or haulback operations is effectually prevented or rendered extremely remote.

Contemplated by the invention is a butt hook wherein the ferruled terminal of the choker cable associated therewith may be inserted either from the open side thereof or through an eye and slot formed in the walls 20 of the same, and which embodies improvements directed particularly to novel hauling line actuated locking mechanism for normally obstructing such open side or eye to positively retain said terminal within the 25 hook when in use; to a crosshead swivel combined with said locking mechanism; and to means for interconnecting the crosshead swivel with the hauling line, all of which are important objects and features of the invention and are to be correlated in the broad aim of enhancing the efficiency of the device for general use.

The above, and additional objects which will hereinafter be more specifically treated, 35 are attained by such means as are shown in the accompanying drawings, described in the following specification and then more clearly pointed out in the claims, which are appended hereto and form a part of this application.

With reference to the drawings, wherein are illustrated several embodiments of the invention, and throughout the several views of which like characters of reference designate similar parts.

Figure 1 is a side elevation of the substantially closed side of a swivelling locking butt hook comprehended by the present invention;

Fig. 2 is a front elevation thereof;

Fig. 3 is an elevation of the opposite or open side of the same;

Fig. 4 is a vertical medial section of the butt hook with the locking member thereof in an unlocked position, as it would appear when coupling the terminal of the choker

cable thereto or uncoupling the same therefrom;

Fig. 5 is a similar section with the locking member in a normally locked position 60 whereby uncoupling of the choker cable terminal from the butt hook is positively prevented;

Fig. 6 is a horizontal section taken through 6—6 of Fig. 5; 65

Fig. 7 is a side elevation of a non-swivelling locking butt hook comprehended by the invention;

Fig. 8 is a front elevation of a modified form of non-swivelling locking butt hook. 70

Fig. 9 is a vertical transverse section taken through 9—9 of Fig. 8;

Fig. 10 is a horizontal section taken through 10—10 of Fig. 8;

Fig. 11 is a front elevation of the same 75 with the locking member thereof illustrated in alternative unlocked positions;

Fig. 12 is a side elevation of a swivelling locking butt hook of modified form; and

Fig. 13 is a similar view of a still further 80 modified form of butt hook.

Before taking up the detailed description of the drawings, a general exposition of the butt hook evolved by the present invention will be undertaken. Heretofore in logging operations the choker cables have occasionally become uncoupled or unhooked from their correlated butt hooks during the yarding of logs, due primarily to slackening or jerking of the hauling lines caused by fouling of such logs upon rough ground or other obstructions, resulting in the temporary loss of the logs and choker cables and expensive delays in the recovery of the same. 90

During haulback operations the choker cables are free to swing from and whip around upon their correlated butt hooks, and because of this fact frequently become unhooked and lost, resulting in the entire logging unit being rendered inactive until 100 such choker cables are recovered, or the rigging is hauled in and replacement choker cables held in reserve for such contingencies are attached thereto.

The butt hooks heretofore in general use, particularly of the types employing ferrules have been fabricated, practically without exception, from cast metal, because of the fact that the structural features and designs of such butt hooks have effectually and positively precluded their manufacture from wrought or forged metal. 105 110

The many disadvantages of the use and employment of cast butt hooks with logging apparatus are well known to those skilled in the art, the principal objection to such hooks being that they frequently break causing the loss of the choker lines and logs, and expensive delays in logging operations.

It is therefore the purpose and aim of the present invention to provide a hauling line locked butt hook, wherefrom the choker cable cannot become unhooked or uncoupled during hauling in or haulback operations, and which may be readily fabricated from wrought or forged metal, whereby a lighter and much stronger butt hook is obtained with much less liability of breakage when in use, than has obtained heretofore where cast butt hooks have been employed.

While the butt hook of the invention may be either forged or cast, the same is preferably wrought or forged in substantially U-shaped formation from a single piece of metal and comprises a lower or bottom wall 15 and vertical walls or cheeks 16 bent or offset inwardly in angular planes adjacent their upper apertured ends to provide thereat angularly and laterally disposed inwardly and upwardly curved shoulders 17 terminating in substantially semi-circular spaced parallel ears 18. The edges of the walls 16 upon one side of the butt hook are bent or turned inwardly between the bottom wall 15 and the ears 18 to form thereon ribs or webs 19 having their opposing edges in alignment with the opposing faces of said ears and extending downwardly therefrom in prolongation thereto, to thereby substantially close said side of the butt hook. The edges of the walls 16 upon the opposite side of the butt hook are similarly bent or turned inwardly to form thereon ribs or webs 20 extending upwardly from the bottom wall 15 and terminating substantially midway between said bottom wall and the ears 18, having their upper ends curved outwardly to merge with the inner faces of the walls 16 adjacent the inwardly and upwardly curved shoulders 17 and in conjunction therewith, form and provide thereat an opening 21, of substantially circular formation, as shown more clearly in Fig. 3. The opposing edges of the ribs 20 form and constitute a longitudinal slot 22 of less width than the diameter of the opening 21 and extends downwardly therefrom to the lower wall 15 to communicate thereat with a lateral slot 23, of similar width, cut in said wall and terminating in a semi-circular end substantially in the center of the same, as shown more clearly in Fig. 6. From the foregoing and by referring to the drawings it will be observed that the side walls 16 conjointly with their correlated ribs 19 and 20 form and provide a socket 24 within the butt hook.

The numeral 25 designates a choker cable

of slightly less diameter than the width of the slots 22 and 23 having a ferrule 26 fixedly secured upon its terminal of a slightly less diameter than the opening 21 and of a greater diameter than the width of the said slots, in order that the choker cable 25 may be rapidly and readily coupled to the butt hook, or similarly uncoupled therefrom.

Interposed between the butt hook ears 18 and pivotally connected thereto by a pin 27 is a laterally swinging locking member 28 having its inner or lower flared end extending within the socket 24 to normally obstruct the opening 21 and having the outer or upper end thereof provided with a swivel cross-head 29, to the ends of which is pivotally connected a shackle or clevis 30, for interconnecting the said swivel crosshead to a terminal link 31 of a hauling line butt chain or tag line.

The choker cable 25 is coupled to the butt hook by swinging the locking member 28 to the unlocked position indicated in Fig. 4, inclining the end portion of the choker cable 25 and inserting the ferrule 26 within the socket 24 through the opening 21, as shown in said figure, and passing the said cable downwardly within the slots 22 and 23, to seat the lower annular face of said ferrule upon the inner face of the lower wall 15 for swivelling movement of the choker cable thereon, as shown in Figs. 1 to 3, inclusive, and in dot and dash lines in Fig. 10, following which a pull on the butt chain or tag line returns or swings the locking member 28 to a normally aligned or locked position within the butt hook to obstruct the opening 21 and prevent unhooking or dislodgment of the ferrule 26 from the socket 24, as more clearly indicated in Fig. 5. The operation of uncoupling the choker cable 25 from the butt hook is the reverse of that hereinbefore described, and will be readily understood.

In Fig. 7 the butt hook of the invention is pivotally connected to a non-swivelling locking member 32 having an eye 33 formed upon the upper end thereof to receive the lower looped end of a relatively short length of cable or chain 34 provided upon the upper end with a terminal ferrule 35 for swivelling movement therewithin a swivel crosshead 36 having a shackle 37 pivotally mounted upon the ends thereof, which receives the outer terminal of a tag line or butt chain 38.

In Figs. 8 to 11, inclusive, a butt hook of slightly modified form having a non-swivelling locking member is disclosed, said butt hook being fabricated from a single piece of flat material of suitable thickness bent in U-shaped formation to provide a lower wall 39 and vertical walls or cheeks 40, one of said walls having an eye 41 cut therein with a slot 42 extending downwardly therefrom to the lower wall 39, wherein said slot laterally extends and terminates in a semi-circu-

lar end substantially in the center of the same.

A choker cable 43 of slightly less diameter than the width of the slot 42 is provided with a ferrule 44 fixedly secured upon its terminal of a diameter slightly less than the diameter of the eye 41 and of a greater diameter than the width of the said slot, so that the choker cable 43 may be rapidly and readily coupled to, or similarly uncoupled from the butt hook, and when coupled thereto is retained therein.

Interposed between and pivotally connected to the semi-circular apertured upper ends 15 of the walls 40 by a pin 44, is a swinging locking member 45 having its inner or lower flared end extending within the butt hook to normally obstruct the eye 41 and having the outer or upper end thereof provided with 20 an eye 46 to receive a terminal link 47 of a hauling line butt chain or tag line.

The choker cable is coupled to the butt hook by swinging the locking member 45 to the alternative unlocked positions indicated in full lines and dot and dash lines in Fig. 11, inserting the ferrule 44 within the butt hook through the eye 41, as shown in dot and dash lines in Fig. 10, and passing said cable downwardly within the slot 42, to 25 seat the lower annular face of said ferrule upon the inner face of the lower wall 39 for swivelling movement of the choker cable thereon, as shown in Figs. 8 and 9, following which a pull on the butt chain or tag line 30 returns or swings the locking member to a normally aligned or locked position within the butt hook to obstruct the eye 41 and prevent unhooking or dislodgment of the ferrule 44 from the butt hook, as will be manifest and apparent. The choker cable is 35 uncoupled from the butt hook by reversing the operation above described.

In Fig. 12 the modified form of butt hook is provided with a pivotally connected locking member 48 having a swivel crosshead 49 mounted upon its outer or upper end, to the ends of which are pivotally connected a shackle 50 for connection with a terminal link 51 of a hauling line butt chain or tag line.

In Fig. 13 the modified form of butt hook is provided with a pivotally connected non-locking, non-swivelling member 52 having an eye 53, to which is connected a terminal link 54 of a hauling line butt chain or tag line.

Manifestly, therefore, the device of the invention is extremely simple, durable and economical in construction, is convenient to use, is positive and efficient in operation, and in the employment thereof much time and energy is conserved.

While I have herein shown and described my invention with sufficient detail to enable those skilled in the art to understand the

mode of construction and the principles involved it is to be understood that there is no intentional limitation herein to the specific form and precise details of construction of the invention herein shown and described except as expressly defined by the appended claims, and that various modifications of said construction may be resorted to without departing from the invention or the benefits derivable therefrom. I also desire to have it understood that certain features of the invention herein disclosed may be employed in other combinations than those herein shown.

Having thus fully described my invention, what I claim as new and desire to secure by Letters Patent is:—

1. In a butt hook, in combination, a body having an opening formed in the walls thereof with a slot extending therefrom, and a member pivotally mounted upon said body having a flaring inner terminal for obstructing said opening.

2. In a butt hook, in combination, a body having an opening formed in the walls thereof with a slot extending therefrom and a swivelling member pivotally mounted upon said body having a flaring inner terminal for obstructing said opening.

3. In combination with a hauling line, of a butt hook attached thereto having an opening formed therein with a slot extending therefrom to accommodate the ferruled terminal of a choker line or the like for swivelling movement within the butt hook, and a member pivotally mounted upon said butt hook having a flaring inner terminal for obstructing said opening.

4. In combination with a hauling line, of a butt hook attached thereto having an opening formed therein with a slot extending therefrom to accommodate the ferruled terminal of a choker line or the like for swivelling movement, within the butt hook and a member connected with and actuated by the hauling line having a flaring inner terminal for obstructing said opening.

5. In combination with a hauling line, of a locking member attached thereto having a flaring inner terminal, a butt hook pivotally mounted upon said member, and a choker line connected to said butt hook and retained therein by said terminal.

6. In combination with a hauling line, of a choker line locking member attached thereto having a flaring inner terminal, a butt hook pivotally mounted upon said member, and a choker line having swivelling connection with said butt hook and being retained therein by said terminal.

7. In combination with a hauling line, of a swivelling locking member attached thereto having a flaring inner terminal, a butt hook pivotally mounted upon said member, and a choker line connected to said butt

hook and retained therein by said terminal.

8. In combination with a choker line having a ferrule on one end, of a hauling line, a butt hook attached to said line having an opening

5 formed therein of greater diameter than said ferrule and a slot extending from the opening of less width than the ferrule and wider than the line diameter, and a member pivotally mounted upon the butt hook having a

10 flaring inner terminal for obstructing said opening.

9. In combination with a choker line having a ferrule on one end, of a butt hook having an opening formed therein of greater

15 diameter than said ferrule and a slot extending from the opening of less width than the ferrule and wider than the line diameter, a swinging member mounted upon the butt

hook having a flaring inner terminal for 20 obstructing said opening, and a hauling line connected to said member for swinging the same.

10. In combination with a choker line having a ferrule on one end, of a butt hook having an opening formed therein of greater 25 diameter than said ferrule and a slot extending from the opening of less width than the ferrule and wider than the line diameter, a swivel member connected at one end to the butt hook having a flaring inner terminal 30 for obstructing said opening, and a hauling line connected to the opposite end of said swivel member.

In testimony whereof I affix my signature.

JESSE F. DRAPER.
